To all whom it may concern:

Be it known that I, PAUL GROEBER, a citizen of the United States, residing at Rutherford, in the county of Bergen, in the State of New Jersey, have invented and produced a new and original Design for Wall-Paper, of which the following is a specification, reference being had to the accompanying drawing, showing a part thereof.

in festoons hanging from ornamental lattice-work, forming the top of the border, as shown. A narrow band of lattice-work is arranged at the bottom of said border, as shown.

What I claim is—
